THE NORRIS PETERS CO., PHOTO-LITHO., WASHINGTON, D. C.

UNITED STATES PATENT OFFICE.

JAMES T. COWLEY, OF LOWELL, MASSACHUSETTS, ASSIGNOR TO THE LAMSON CONSOLIDATED STORE SERVICE COMPANY, OF NEWARK, NEW JERSEY.

PNEUMATIC-DESPATCH APPARATUS.

SPECIFICATION forming part of Letters Patent No. 680,699, dated August 20, 1901.

Application filed November 27, 1899. Serial No. 738,331. (No model.)

To all whom it may concern:

Be it known that I, JAMES T. COWLEY, of Lowell, in the county of Middlesex and State of Massachusetts, have invented certain new and useful Improvements in Pneumatic-Despatch Apparatus, of which the following is a specification.

My invention relates to new and useful improvements in pneumatic-despatch apparatus; and the object is to provide an improved receiving-terminal for receiving and delivering carriers.

My invention consists of certain novel features hereinafter described, and particularly pointed out in the claims.

In the accompanying drawings, which illustrate a construction embodying my invention, Figure 1 is a side elevation of the terminal with part of one side removed to show interior parts. Fig. 2 is a side elevation of the terminal with part of one side removed, showing the interior mechanism in a different position from that shown in Fig. 1 and in normal position. Fig. 3 is a front elevation of the terminal. Fig. 4 is a detail view of the top of the terminal. Fig. 5 is a side sectional view of the valve closing the lower end of the terminal with part of the discharge-tube in full lines. Fig. 6 is a sectional view on the line xx , Fig. 2. Fig. 7 is a detail of the trip mechanism.

Like letters of reference refer to like parts throughout the several views.

The tube B, extending from the opposite end of the line, passes up through the terminal C, and the upper end extends above the terminal C and is provided with a cover B', closing the upper end of the tube. (See Fig. 4.) The carrier passing up through the tube B in the direction of the arrow, Fig. 2, all the parts within the terminal C being in the position shown in Fig. 2, the carrier will first engage with the trip-lever B², mounted on the bearing B³ and having at its opposite end a catch B⁴, engaging with the catch B⁵ on the lever B⁶, which is pivoted at B⁷ to the sides of the terminal C. Pivoted at C' is another switch-lever C², which in its normal position is held in the position shown in Fig.

2. This lever has a flat spring C³, against which the upper end B⁸ of the lever B⁶ bears. The upper end of the switch-lever C² bears against the cushion C⁴, secured in the upper end of the terminal C. Secured to the lower end of the switch-lever C² is a link C⁵, to the opposite end of which is connected one end of the spring C⁶, the opposite end being secured at C⁷ to the bottom of the terminal. The carrier passing upward through the tube B and engaging with the lever B², as above described, will move the catch B⁴ out of engagement with the catch B⁵ on the lever B⁶, allowing the spring C⁶ to move the switch-lever C², carrying with it the lever B⁶, to the position shown in Fig. 1, the upper end of the switch-lever C² resting on the cushion C⁴ in the upper end of the terminal C. Before the lever C² moves over to the position shown in Fig. 1 the carrier will have passed above the lever C² and entered the upper end of the tube B, closed by the cover B', and the carrier is cushioned by the air confined within the tube in front of the carrier. The carrier after being cushioned and losing its momentum will drop back by gravity and be guided by the switch-lever C² (which has been moved over, as shown in Fig. 1, as above described) into the branch tube D of the terminal C and pass down through said tube by gravity and engage with the lower end of the lever B⁶, which is then in the position shown in Fig. 1, and move the lever B back to the position shown in Fig. 2, so that the catches B⁴ and B⁵ will again engage with each other and restore the parts to the position shown in Fig. 2. When the carrier first strikes the lever B⁶, the flat spring C³ will yield and allow the lever B⁶ to move into engagement with the catch B⁴ before the switch-lever C² has moved to the position shown in Fig. 2, and by this arrangement the instantaneous moving of the entire weight of the parts is avoided, as the spring C³ will gradually return the lever C² to its normal position, (shown in Fig. 2,) and also if two carriers should be passing through the terminal at once there would be sufficient time for both carriers to pass into the tube D and restore the lever B⁶ to its normal position.

mal position before the lever C² moves to its normal position, Fig. 2. After the carrier has passed by the end of the lever B⁶ it will engage with and open the valve D', held in its closed position by the spring D³, and the carrier will then pass downwardly into the tube D³ of the terminal C, the spring D³ restoring the valve D' to its normal position. The carrier will continue its downward course in the tube D³ and will cushion upon the air confined within said tube before it has reached the lower end of the tube. The lower end of the tube D³ is surrounded by a casing D⁴, which is provided with lugs D⁵, upon which is journaled the lever D⁶. This lever carries at its outer end the valve D⁷, closing the lower end of the tube D³. This valve is provided with a cushion D¹⁰, upon which the carrier strikes when it reaches the lower end of the tube D³. Mounted on the valve D⁷ is a plate D⁸, which engages with the lower end of the catch E. The upper end of this catch E is securely fastened at E' to the shaft E², which passes through the chamber E³ within the casing D⁴. On the shaft E² and within the casing D⁴ is mounted the curved lever E⁴, held in its outward position by the spring E⁵ in position to be engaged by the carrier when it has passed down through the tube D³. This catch E will hold the valve D⁷ closed against the pressure of the air in front of the downwardly-moving carrier in the tube D³ until the carrier reaches the lower end of the tube and is cushioned by the air within the tube D³. When the carrier reaches the lower end of the tube D³, it will engage with the lever E⁴, and through the connections of the shaft E² and catch E the valve D⁷ will be released and the weight of the carrier will open the valve and the carrier will pass out of the tube D³ and into any suitable receptacle. The weight D⁹ on the opposite end of the lever D⁶ will return the valve D⁷ to its normal position in engagement with the catch E. As the carrier passes upwardly through the tube B and above the lever C², as above described, in order that the compressed air in front of the carrier at the outer end of the tube B may not check the momentum of the carrier before the carrier has passed above the lever C² the tube F is provided, connecting at its upper end with the tube B and passing downwardly by the terminal C and entering the tube B again at F'. (See dotted lines, Figs. 1 and 2.) The object of this is to provide a passage for the air from in front of the carrier as it enters the upper end of the tube B above the terminal C. After the carrier is cushioned in the upper end of the tube B and returns by gravity and is guided into the tube D, as above described, it is also guided by the plates G, located within the terminal and flush with the inside diameter of the tube B. After the carrier has passed above the lever B² the latter is returned to its normal position by the spring G' in position to engage with the catch B⁵ when the

lever B⁶ is moved into its normal position. (Shown in Fig. 2.) The air in its passage upwardly through the tube B in the direction 70 of the arrow shown in Fig. 2 will pass out of the tube B through the elongated opening H and into the space H' around the tube B' in the direction of the arrows within the terminal, Fig. 2, and will pass down through 75 the tube J, leading to a suitable exhaust apparatus for maintaining circulation of air within the tubes.

I do not limit myself to the arrangement and construction shown, as the same may be 80 varied without departing from the spirit of my invention.

Having thus ascertained the nature of my invention and set forth a construction embodying the same, what I claim as new, and desire to secure by Letters Patent of the United States, is—

1. In a pneumatic-despatch apparatus, an inlet and an outlet for the carrier, a switch-lever for guiding the carrier to the outlet, 90 means for holding said lever out of its switching position, means for moving said lever into its switching position, mechanism actuated by the traveling carrier for releasing said switch-lever to allow it to move into its 95 switching position, and means for cushioning the carrier and retarding its travel before it is diverted by said switching-lever to the outlet.

2. In a pneumatic-despatch apparatus, an 100 inlet and an outlet for the carrier, a switch-lever for guiding the carrier to the outlet, means for holding said lever out of its switching position, means for moving said lever into its switching position, mechanism actuated 105 by the traveling carrier for releasing said switch-lever to allow it to move into its switching position, mechanism located in the outlet and actuated by the traveling carrier for returning the switch-lever to its normal position, and means for cushioning the carrier and 110 retarding its travel before it is diverted by said switching-lever to the outlet.

3. In a pneumatic-despatch apparatus, an 115 inlet and an outlet for the carrier, a switch-lever for guiding the carrier to the outlet, means for holding said lever out of its switching position, means for moving said lever into its switching position, mechanism actuated by the traveling carrier for releasing said switch- 120 lever to allow it to move into its switching position, a lever located in the outlet and actuated by the traveling carrier for returning the switch-lever to its normal position, and a yielding connection between said lever and 125 the switch-lever.

4. In a pneumatic-despatch apparatus, an 130 outlet for the carrier, a pivoted valve for closing said outlet, means for holding said valve closed, mechanism located adjacent to said valve and in the path of the traveling carrier and actuated thereby to move said valve-holding means and thereby allow said valve to open, and means for automatically closing

said valve after the carrier has been discharged.

5. In a pneumatic-despatch apparatus, an inlet and an outlet for the carrier, a switch-
5 lever for guiding the carrier to the outlet, means for holding said lever out of its switch-
ing position, means for moving said lever into its switching position, mechanism actuated by the traveling carrier for releasing said switch-
10 lever to allow it to move to its switching position, means for cushioning said carrier and re-
tarding its travel before it is diverted by said switching-lever to the outlet, a valve nor-
mally closing said outlet, means for holding
15 said valve closed, mechanism located adj-

cent to said valve and in the path of the trav-
eling carrier and actuated thereby to move
said valve-holding means and thereby allow
the valve to open, and means for automatic-
ically closing said valve after the carrier has 20
been discharged.

In testimony whereof I have signed my name to this specification, in the presence of two subscribing witnesses, this 14th day of November, A. D. 1899.

JAMES T. COWLEY.
